COMBINED TYPEWRITING AND COMPUTING MACHINE

Henry L. Pitman, Hartford, Conn., assignor to
Underwood Elliott Fisher Company, New York,
N. Y., a corporation of Delaware

Application April 20, 1938, Serial No. 203,118

4 Claims. (Cl. 235—130)

This invention relates to typing machines, and deals with control-mechanism by means of which it is made certain automatically that only a particular one or more of a complement of digit-keys, types, or digit-indexers, and no others, can be used at a predetermined letter-space or denominational position of the typing carriage.

The invention is herein explained with reference to a combined typing and computing machine of the Underwood-Hanson class wherein, at operation of digit type-keys to type an amount, digit by digit, digit-indexers are concomitantly operated so that the amount is set up in computing-wheel drivers or register-bars that are denominational selected under control of the typing carriage; the register-bars being subsequently cycled to run the indexed amount into computing wheels.

In a machine of this class, adapted for computing in sterling money denominations, no type-key or digit-indexer other than that for the digit 1 need ever be used when the typing carriage is at the position for typing or indexing in the tens-of-shillings denomination, since no number of shillings higher than 19 is ever typed or indexed.

Similarly, when the carriage is at the position for typing or indexing at the farthings denomination, no type-key or indexer other than for 1, 2 or 3 farthings need ever be used.

In one form of the invention, the digit type-keys and indexers for 1, 2 and 3 are also used for typing and indexing farthings in that said type-keys may operate either lower-case types for printing the digits 1-3 or upper-case types for printing the fractions $\frac{1}{4}$, $\frac{1}{2}$, $\frac{3}{4}$ to express fractional pence or farthings.

In another form of the invention the digits may be typed in either one of two styles to distinguish, for example, credit and debit amounts, one style being expressed by lower-case types that are normally used, and the other style being expressed by upper-case types selected through operation of a case-shift mechanism. In this form of the invention the digit-keys 1-3 are not available for typing farthings-expressing fractions in upper case. Therefore, three other keys are provided and may be restricted to typing only farthings; and, further, these three keys may type and express farthings in either one of said two styles to distinguish credit and debit sterling amounts.

An object, in either form of the invention, is to provide a reliably operative and durable key-locking structure adapted to insure that none but the appropriate portion of type-keys can be op-

erated when the carriage is at the position for typing in such denominations as tens-of-shillings, or farthings.

Another object in the first-mentioned form of the invention is to have all the amount-typing keys primarily and automatically locked by reason of the carriage being at the farthings denomination. This apprises the typist of the need to case-shift to determine typing and expressing the farthings by means of the digit-keys 1-3 and the upper-case fraction types.

Another object is that pursuant to the operation of the case-shaft mechanism for typing with the upper-case fraction types by means of the digit-keys 1-3, only these keys shall be left unlocked, leaving the remaining digit-keys locked as long as the carriage is at the farthings-denomination position.

An object in the second form of the invention employing three extra farthings keys, for 1, 2 and 3 farthings, besides the digit-keys 1-3, is that either the digit-keys 1-3, or the farthings keys for 1, 2 or 3 farthings, may operate, respectively, the same digit indexers 1-3 in the computing mechanism.

Another object in the second form of the invention is to have all the numeral keys, including the three extra farthings keys, locked at a tens-of-shillings-denomination position of the carriage, except the key for typing the digit 1; and to have all the numeral keys, except said three farthings keys, locked when the carriage is at a farthings-denomination position.

Other features and advantages will hereinafter appear.

In the accompanying drawings:

Figure 1 is a cross-sectional side elevation of the combined typing and computing machine including parts embodying the invention.

Figure 2 is a perspective, showing the arrangement of the key-locking mechanism for the amount keys whereof digit-keys 1-3, operable in lower case, are also used for typing the farthings in upper case.

Figure 3 is a perspective, showing an arrangement of key-locking mechanism for a set of keys that includes, besides the digit-keys 1-3, separate keys for typing the farthings.

Figure 4 is a side view diagram illustrating said separate keys for the farthings.

Figure 5 is a keyboard diagram wherein, in addition to a row of amount or digit-keys, there are three separate keys for farthings.

Figure 6 is a keyboard diagram wherein the

digit-keys 1-3, operable in lower case, are used in upper case for typing farthings.

Figure 7 is a perspective of the carriage and case-shift mechanism and including carriage-operated jacks of the denomination-selecting mechanism, and connections from certain ones of said jacks to the key-locking mechanism, the view being sectioned in part for clarity.

Figure 8 is a large-scale perspective, illustrating connections whereby certain jacks control the key-locking mechanism.

Figure 9 is a diagram of elements adapted to lock different ones of the Figure 5 amount keys at different denominations of the carriage.

Figure 10 is a diagram similar to Figure 9 but showing key-locking elements adapted for amount keys of the Figure 6 keyboard.

Figure 11 is a plan-view diagram of a sterling-computing-register mechanism in the computing base shown at Figure 1.

Figure 12 is a diagram of the complement of numeral types showing upper-case types for farthings on the same type-bars that include the digit-types 1, 2, 3.

Figure 13 is a diagram of the complement of numeral types wherein lower-case types, including farthings types, and upper-case types, including farthings types, are of different styles to distinguish different kinds of amounts.

A typewriter unit T, Figure 1, is mounted upon a computing base CB. The typewriter frame 20 has front and rear rails 21 upon which a typing-carriage 22 reciprocates. Depression of any numeral-type-key lever 23 about a fulcrum 24 acts through a bell-crank 25 to swing a type-bar 26 upwardly and rearwardly about fulcrum 27 to print against a platen 28 journaled in a frame 29 supported in known manner by the carriage 22 for up and down case-shift movement with the platen.

A case-shift rail 32 forms part of a frame 33 including a rear cross-rod 34 at which said frame is pivoted at its sides to the typewriter frame 20 for turning clockwise from the Figure 1 normal position to a position wherein the rail 32 is elevated and has thereby, through engaging a roll 35 on the platen frame 29, elevated the latter to upper-case position to receive impressions from upper-case types 36 instead of from lower-case types 37.

Each type-bar 26 causes a universal bar 38 to be actuated to reciprocate escapement dogs 39 relatively to an escapement wheel 40 thereby causing a spring motor 41 to advance the carriage 22 in a letter-feed step by means of an escapement-wheel pinion 42 and a pinion-engaging rack 43 on the carriage.

At the depression of any numeral-key lever 23 a pendent rod 45 thereon engages an arm 46 of a corresponding one of a series of rock-shafts 47 to rock the shaft to depress a corresponding one of a series of indexing bars 48, each rock-shaft 47 engaging, as at 49, a bar 50 to move the latter endwise and thereby, through end bell-cranks 51, Figures 1 and 7, depress the corresponding indexing bar 48.

Register-bars 52 in the computing base are normally in such position that depressible index pins 53 thereon are out of the paths of descent of the indexing bars 48, as in Figure 1. The register-bars are slightly advanceable seriatim, under denomination-selection control of the carriage, against spring devices 54, to bring their pins 53 under the indexing or pin-setting bars 48.

For control of the register-bars denomina-

ally, the carriage carries, for each computing zone, a denomination-selecting tappet 55 to override and depress a series of denomination jacks 56. The jacks are slidably retained in upper guides 57 and lower guides 58 in a housing 59 attached to the typewriter frame 20. Aligned with the set of denomination jacks 56 is a companion set of thrust rods 60 in the computing base, the latter having a rack 62 for slidably guiding said thrust rods at their upper ends. Each thrust rod works, at the depression of the corresponding jack 56, to rock an individual bell-crank 63 to move forwardly a master rack 64. Each master rack 64 is connected, as at 65, to a corresponding one of a set of transverse blades 66 adapted to be rocked forwardly individually about their lower edges, rockably retained as at 67, to move a distributive rack 68, that is opposite a corresponding register-bar 52, forwardly to bring the pins 53 of the latter under the pin-setting bars 48 when the corresponding jack 56 is depressed.

Each distributive rack 68 has pivoted thereto a coupler 70 which is normally dropped clear of the corresponding register-bar 52. The computing base may have several sets of register-bars 52 and each set is connectible to a corresponding set of distributive racks 68 that are connected, like the master racks 64, to the single set of transverse blades 66.

A register-bar set is selected, under control of the carriage, by raising into operative alignment therewith, the set of couplers 70 of the corresponding distributing racks 68. For each computing zone, the carriage carries one or more register-selecting tappets 71 to engage and depress, selectively at a computing zone one or more cam-plates 72 slidably guided in the housing 59, the several cam-plates engaging at their lower ends, as diagrammatically represented by the dot-and-dash line 73, Figure 1, thrust rods 74, guided at 69 in the computing base. The depression of a cam-plate 72 and corresponding thrust rod 74 operates, through a corresponding linkage 75, to rock a corresponding shaft 76 which, through a crank 77, raises a plate 78 to raise a corresponding set of couplers 70 into operative alignment with the corresponding set of register-bars 52.

The several rock-shafts 76, one for each set of register-bars, are journaled in a cross-member 80, Figure 1, of the computing-base frame, which also supports a frame 81 slidably mounting the master and distributive racks 64, 68, and rockably mounting the cross blades 66. The coupler-lifting plate 78 is slidably guided by means of studs 82 in a plate 83 that slidably supports the register-bars 52.

The carriage may be tabulated denominational to a computing zone by raising the appropriate one of denominational stop-reeds 85 by means of its denominational tabulating-key 86 into the path of a computing zone or column stop 87 on the carriage, the carriage being released from the escapement pinion 42, for the tabulating jump, concomitantly with the raising of the stop-reed 85. The stop-reeds 85 have known connections (not shown) to their keys 86. At the tabulated-to denomination the tappet 55 depresses the corresponding jack 56 to advance slightly the master rack 64 of corresponding denomination, and, by means of the cross-blades 66, slightly advance all the distributive racks 68 of the same denomination in the several sets of said distributive racks. This causes all the bars

52 of the same denomination, in those sets for which the couplers 70 have been raised to the Figure 7 position, to be slightly advanced to bring their digit pins 53 under the pin-setting bars 48. Thus, at the depression of a numeral-key lever 23 to type a digit at the selected denomination, the corresponding digit-pin-setting bar 48 depresses the corresponding digit-pin or pins 53 in each register-bar or bars that have been slightly advanced. The key 23 having been operated and the digit typed, the carriage steps, by means of the escapement mechanism, to the next denomination to depress the next jack 56 and thereby slightly advance the next register-bar or bars of said next denomination. As the carriage leaves a depressed jack 56, the latter and the thereby advanced register-bar or bars 52 and intermediate parts become restored as by means of the spring devices 54 and master-rack springs 88. Thus, at the typing of an amount in a computing zone, the appropriate digit pins 53, for the digits of the amount, are depressed, denomination by denomination, in the set or sets of register-bars for which the couplers 70 have been raised by means of the register-selecting tappets 71 on the carriage.

The digit pins 53, when depressed, project into the path of a reciprocating general-operator cross-bar 89, Figure 1, which is cycled after the indexing operation. Side racks 90 at the sides of the computing-base frame are connected, by means of a cross-shaft 91, journaled in said frame, and gears (not shown) to reciprocate in unison. Said side racks 90 carry said general-operator cross-bar for reciprocative movement. At the advance (to the left of Figure 1) of the cross-bar 89, the latter engages the depressed digit pins 53 to advance the register-bars 52 to extents corresponding to their depressed pins 53.

Computing-wheel pinions 92 are adapted to mesh either directly with racks 93 of the register-bars or with intermediate idlers 94 so as to be rotated additively or subtractively by the advance of the register-bars. The machine may have a plurality of sets of computing pinions 92 and their dials 97 as represented diagrammatically at Figure 11, and it will be understood that each set has its set of register-bars 52 and idlers 94. Carry-over devices 95, Figure 1, are adapted to advance the register-bars 52 extra carry-over steps beyond the range of movement of the general-operator cross-bar 89. Preparatory to the return stroke of the cross-bar 89 (to the right of Figure 1) the computing-pinions 92 are caused to be unmeshed from the racks 93 or idlers 94. In its return stroke, the general-operator cross-bar 89 engages shoulders 96 of the advanced register-bars to restore them to the Figure 1 position.

The totalizer-mechanism, including the register-bars 52 and computing-pinion dials 97, is adapted to compute in English or sterling money denominations. Referring to Figure 11, the first computing dial 97 from the right of the illustrated sterling register is for farthings, the next two dials are for units pence and tens pence and are coupled by a hub 99 to rotate in unison. The next dial is individually rotatable and computes units-of-shillings; and the next dial to the units-of-shillings dial is also individually rotatable and computes tens-of-shillings. The remainder of 70 the dials in Figure 11, namely the first four dials from the left are each individually rotatable to compute pounds.

Each dial 97 has attached thereto its individual pinion 92 to mesh with the rack 93 of the cor-

responding register-bar 52 or with the idler 94 that meshes with such rack; except that the two pence dials 97 that are coupled together by the hub 99 have a common pinion 92 attached to the units-of-pence dial and meshing with the pence register-bar rack 93 or its idler 94. The farthings computing pinion 92 and the pence computing pinion 92 and their respective racks 93 and idlers 94 are adapted for twelve steps of rotation in a revolution of each of said pinions. The farthings dial has four steps between recurring zero positions and, therefore, its register-bar 52 has four index pins, including a zero pin. The coupled pence dials have twelve steps of rotation from zero to zero, and, therefore, the pence register-bar 52 has twelve index pins, including a zero pin. The tens-of-shillings dial has two steps between recurring zeros and its register-bar 52 therefore has two index pins, including a zero pin. Each of the other register-bars in the set drives a ten step dial and, therefore, has ten index pins 53, including a zero pin. The arrangement, Figure 11, is such that, normally all the zero pins stand in a transverse row. 25 The 1 pins stand in a succeeding transverse row, and so on up to the 9 pins. The 10 and 11 pins of the pence bar stand ordinally in succession behind the 9 row of index pins.

The general-operator cross-bar 89 has an idle period at the beginning of its advance stroke, before it may pick up the highest or 9 pin of any ten-pin register-bar 52. This idle period affords time for meshing the computing pinions 92 either with the register-bar racks 93 or with 30 the idlers 94 before the general operator advances any register-bars. The general-operator cross-bar 89 has a nine-step range of movement after engaging any 9 pin 53. But during this nine-step movement, the general-operator cross-bar 89 must be capable of advancing the pence register-bar eleven steps. In order to do this, an auxiliary bar 100, generally similar to and mounted for reciprocating movement like the register-bars, is disposed to the left of the pence register-bar 52, Figure 11, and has a laterally-projecting tab 102, Figure 1, standing behind the 11 pence pin. Said auxiliary bar has a rack 103 meshing with a sector 104 pivoted as at 101 to the general-operator cross-bar 89. Said sector 104 has an arm 105 extending downwardly and normally engaging a fixed stop 106 as in Figure 1. At the first part of the advance of the general-operator cross-bar 89 the sector 104 45 rolls idly along the auxiliary bar rack 103 and finally stops against the top of the general-operator cross-bar 89. This idle movement of the sector 104 corresponds to the idle period or said first part of the general-operator advance, and affords time for meshing the computing pinions with the racks 93 or idlers 94. Further movement of the general-operator cross-bar 89 then carries the auxiliary bar 100 along so that its tab 102 picks up and advances the pence register-bar 52 by means of whichever pin 53 is set in the latter. Near the end of the general-operator advance, the sector arm 105 encounters an arm 107 of a carry-over lever 108 fulcrumed on a stationary rod mounted in the framework. The completion of the forward movement of the general-operator cross-bar after such encounter of arm 105 with arm 107, causes the sector 104 to be rotated counter clockwise of Figure 1 sufficiently to advance the auxiliary bar 100 and pence register bar 52 two steps in addition to

their advance resulting from the nine-step advance of the general-operator cross-bar 89.

At a carry-over step from farthings to pence, the farthings wheel rocks a carry-over trip lever 109 to trip a latch bar 110 connected to the carry-over lever 108 causing the latter to be rocked counter-clockwise of Figure 1 to project its arm 107 one step farther into the path of the sector arm 105. This causes an additional or carry-over step of rotation of the sector 104 and a corresponding additional advance of one carrying step of the auxiliary bar 100 and pence register-bar 52.

The jacks 56 correspond to the sterling denominations of the described register, Figure 11, and range in descending denominational order from right to left. Thus, the first four jacks from the right, Figure 8, are pounds denominations jacks. The next jack 111 is a punctuation-space jack. The next two jacks 56 are the tens-of-shillings jack and the units-of-shillings jack. The latter is followed by another punctuation-space jack 112. The next jack 56 is the pence jack; and the last jack, shown engaged by the tappet 55, Figure 8, is the farthings jack. The master racks 64 have the same descending order, from right to left, as the jacks 56, and this order is transposed in the set or sets of distributive racks 68, by transposing the order of connections of the latter to the cross-blades 66 relative to the connections 65 of the master rocks 64 to said cross-blades.

A jack 113 has a pin-and-slot connection 114 to a cycle-trip lever 115 pivoted on the typewriter framework and engaged by a cycle-trip tooth 116 on the carriage in the step that the latter leaves the farthings jack 56. Said jack 113, when depressed by means of said tooth 116 and lever 115, works through a thrust rod 117 and a bell-crank 118, Figure 7, engaging a lever comprising an arm 119 connected by a yoke 119a to an arm 119b, Figure 1, said lever being loosely fulcrumed on a rod 120 mounted in the computing base, to rock a cycle-trip shaft 121 journaled in the computing base and connected to said lever as at 122, Figure 1. Mechanism, not shown, responds to the rocking of said shaft 121 to effect a single revolution cycle of a shaft 123 journaled in the computing base and adapted, by connections, not shown, to reciprocate the general-operator cross-bar 89.

A lever 125, Figure 1, loosely fulcrumed on the rod 120 is depressible, by means of a link 126, to displace a cam-arm 127, fixed to a rock-shaft 128 journaled in the framework, and thereby rock said shaft 128 to withdraw a latch 129, carried by said shaft 128, from a latch-plate 130 fixed to a rock-shaft 131 journaled in the framework. The resultant rocking of said shaft 131 clockwise of Figure 1 displaces the bell-cranks 63 rearwardly to disable the jacks 56 and also disables the linkage 75 to disable the cam-plates 72, as will be obvious from Figure 1. In the cycling of the shaft 123 a cam roll 123a thereon operates to restore the latch-plate 130 to the Figure 1 latched position, thereby restoring effectiveness of the jacks 56 and cam-plates 72. The cycling of said shaft 123 is effected at upward movement of the lever 125 engaging a pawl 132 to rock the cycle-trip rock-shaft 121.

The foregoing description of the machine will be found sufficient for an understanding of the invention relating to the key and key-locking mechanisms to be described presently. The tab-

ulating key and stop mechanism may be as shown in Patent 1,858,447 to W. F. Helmond dated May 17, 1932. Denomination-selection of the register-bars by means of cross-blades such as 66 is substantially like that in Patent 2,090,852 to H. L. Pitman, dated August 24, 1937. The Pitman patent, 1,927,951, dated September 26, 1933, describes additive or subtraction operation of the computing pinions by the register-bars and the carry-over devices. The jack-silencing mechanism is substantially like that described in my co-pending application, Serial No. 72,348, filed April 2, 1936, now Patent No. 2,160,487, dated May 30, 1939; and my co-pending application, Serial No. 654,057, filed January 28, 1933, now Patent No. 2,156,481, dated May 2, 1939, describes more fully the mechanism for advancing the pence bar eleven steps by the nine-step movement of the general-operator cross-bar 89.

The key mechanism and key-locking mechanism will now be described with reference to the described sterling register mechanism.

Referring to Figures 2, 6 and 10, twelve numeral keys 133 ranging in value from 0 to 11 are provided. Each key 133 has its key-lever 23 having the pendent rod 45; and there are also provided twelve of the pin-setting bars 48 depressible by means of the rods 45. The keys from 0 to 9 are used for typing (lower case) and indexing pence, shillings and pounds from 0 to 9. The 1 key is used for indexing 1 at the tens-of-shillings denomination of a sterling amount and concomitantly typing 1 in lower case on the corresponding type-bar 26. The keys from 1 to 3 are used also for indexing the farthings pins 53 in the farthings register-bar 52, Figure 11, and concomitantly typing farthings with upper-case characters 1/4, 1/2 and 3/4, provided on the same type-bars 26 that ordinarily type the numbers 1 to 3 in lower case. The keys 133 marked 10d and 11d are used only for setting respectively the 10 and 11 pins 53 in the pence register-bar 52, Figure 11, and concomitantly typing 10 or 11 with lower-case characters on the corresponding type-bars 26 at a pence denomination of a sterling amount.

Referring now to Figures 7 and 8, the punctuation-space jacks 111, 112 have each a pin-and-slot connection 134 to a bail 135 pivoted as at 136 to the housing 59. Said bail 135 also has a pin-and-slot connection 134 to a dummy jack 137 slideable in the housing 59 and engaging at its lower end a thrust rod 138 pivoted to a bell-crank 139. Thus, at depression of either punctuation-space jack 111 or 112 by the carriage tappet 55 at a punctuation-space position of the carriage, said dummy jack 137 is depressed, thereby rocking the bell-crank 139 clockwise of Figure 7, to rock a lever 140 fulcrumed on the rod 120, clockwise. The lever 140, thus rocked clockwise, draws rearwardly a link 141 to rock a shaft 143, journaled in the computing base, counter-clockwise of Figures 1 and 7, thereby lifting an arm 144 fixed to said rock-shaft 143. By its lift said arm 144 rocks a lever 146, pivoted on a plate 145, Figure 1 or 2, counter-clockwise of Figure 2 to thereby interpose a tongue 148 of said lever into a row of lock-elements 149, Figures 1, 2 and 10. The row of lock-elements 149 is retained in a groove 150 of a cross-bar 151 fixed to the typewriter-frame and having the plate 145 over said groove to retain the lock-elements. The row of lock-elements is confined at its ends as by means of stops 152 so that a space between any two lock-elements can be spread only far

enough to admit a shoulder 153 formed on each of the pendent rods 45. The row of lock-elements 149 is split as at 154, Figure 10, to admit the tongue 148 of the lever 146, and when said tongue is admitted at 154, through depression of either one of the punctuation-jacks 111, 112, the row of lock-rods is closed against admission of the shoulder 153 of any of the pendent rods 45, thereby substantially locking all of the twelve numeral keys 133, their key-levers 23 and indexing pendent rods 45 against depression at a punctuation-space of the carriage. Each pendent rod 45 passes through a clearance or guide slot 155 in the lock-element retaining-bar 151 to dispose its lower end in operating range of the corresponding arm 46 of the pin-setting mechanism.

The farthings jack 56, when depressed by the tappet 55, as in Figure 8, operates the described all-keys-locking mechanism when the platen is in lower-case position, in order to apprise the typist of the need to shift to upper case for typing the farthings characters 1/4, 1/2, or 3/4. For this purpose a stud 157 on the farthings jack 56 serves, when the latter is depressed, to depress an interponent bar 158 adapted to engage a lateral tongue 159 on the punctuation-space jack 112, thereby depressing the latter and the dummy jack 137 to interpose the tongue 148 between the lock elements 149 to lock all of the keys 133 and their corresponding key-levers 23, pendent indexing rods 45 and type-bars 26.

Said interponent bar 158 is linked at 160 to an arm 161 fixed to the cross-rod 34 of the case-shift frame 33. Thus, when the latter is rocked, clockwise of Figures 1 and 7, to upper-case position by depressing a farthings case-shift key-lever 162 about its fulcrum 163, Figure 7, said interponent bar 158 is drawn forwardly to bring an end-reducing cam bevel 164 thereof under the farthings jack stud 157 to permit a punctuation-jack restoring spring 165 on the bail 135 to restore the jacks 112, 111, 137 and thereby permit restoration of the lever 146 as by a spring 166, Figure 1, to retract the tongue 148 of said lever from key-locking engagement between the lock-elements 149.

It will be perceived now that all the numeral keys have first been locked by means of the farthings jack 56 and lock-elements 149 when the platen is in lower case and the carriage is at a farthings denomination. This apprises the typist of the need for case-shifting preparatory to typing farthings in upper case. It will further be perceived that depression of the farthings case-shift key-lever 162 unlocks not only the three keys allotted for farthings, but also unlocks all of the other numeral keys through retraction of the tongue 148 from the lock-elements 149. It is desired, nevertheless, to have all of said other keys (the last 9 keys to the right of Figure 2) locked while the farthings keys are operable so that none of said other keys may be inadvertently operated. This is accomplished by an auxiliary key-locking mechanism which will now be described.

The distributive rack 68, Figure 2, for the farthings denomination, has an arm 168 having a pin-and-slot connection 169 to an arm 170 fixed to a rock-shaft 171 journaled in brackets 172 mounted on bars 173 suitably fixed, as by attachment to the frame 81. Another arm 174 fixed to said rock-shaft 171 has a pin-and-slot connection 175 to a link 176. A spring 177 yieldably holds the pin and one end of the slot of 75

said connection 175 in abutment, as at Figure 2, so that clockwise rotation of the rock-shaft 171, effected by the slight advance of said farthings distributive rack 68 through depression of the farthings jack 56 draws said link 176 rearwardly. Thereby, said link 176, articulated as at 178, to a bell-crank 179, turns the latter clockwise of Figure 2 about a pivot 180 on a bracket 181 supported as by attachment to a frame 182 that supports the rock-shafts 47 and other parts of the pin-setting mechanism. Said bell-crank has a pin-and-slot connection 184, Figure 2, to a transverse key-locking bar 185 resting slidably on another key-locking bar 186 that is provided for a purpose to be described later. Said latter key-locking bar 186, rests slidably on studs 187 projecting from the frame 182, and may also rest slidably on a shelf 188, Figure 10, attached to said frame 182 and having a pin-and-slot connection 189 to said bars 185, 186 adapted to permit endwise movement of and slidably retain said bars laterally. Each bar 185, 186 has cutouts or notches 190 so that in the normal or non-locking position of said bars, as shown at line A of the Figure 10 diagram, spurs 191, Figure 2, of the pendent key-lever rods 45 may pass said bars 185, 186 freely, through said notches, and thus normally permit any one of all the numeral key-levers 23 to be actuated.

The clockwise displacement of the bell-crank 179, through depression of the farthings jack 56, shifts the key-locking bar 185 leftward to a position relatively to the pendent rods 45 as in the line B of the Figure 10 diagram. The notches 190 and adjacent unnotched portions 192 of the key-bar 185 are so proportioned that in said line B position the spurs 191 on the pendent rods 45 for the farthings keys 133, namely, the first three keys from the left of Figure 10, are free to pass the key-locking bar 185 in said position, while the unnotched portions 192 adjacent the notches 190 associated with the pendent rods 45 of the remaining nine keys are under the spurs 191 of these latter rods 45 and thus prevent operation of any one of said nine keys when the farthings keys are operable.

The underlying bar 186 is for locking all but the 1 key-lever 23 when the carriage is at the tens-of-shillings denomination of a computing zone 50 and has therefore depressed the tens-of-shillings 55 denomination jack 56. The distributive rack 68, Figure 2, associated with said tens-of-shillings jack has an arm 194 having a pin-and-slot connection 195 to an arm 196 loosely fulcrumed on the rock-shaft 171 and connected by a yoke 197 to another arm 198 that is also loosely fulcrumed on said rock-shaft 171. Said arm 198 is connected by a pin-and-slot connection 175 and spring 177 to a link 199 similarly to the connection of the link 176 to the arm 174. Said link 199 is articulated as at 200 to a bell-crank 201 underlying the bell-crank 179 and fulcrumed on the same pivot 180. Said bell-crank 201 has a pin-and-slot connection 202 to the lower key-locking bar 186.

Thus, when the tens-of-shillings jack 56 is depressed and the tens-of-shillings distributive rack 68 is consequently slightly advanced, the arms 196, 198 are rocked clockwise on the shaft 171 pulling the link 199 rearwardly to turn the bell-crank 201 clockwise of Figure 2 and thereby shift the lower key-locking bar 186 leftward to a position relatively to the pendent rods 45 as illustrated in line C of the Figure 10 diagram. In said line C position, unnotched portions 192 of

the bar 186 are under the spurs 191 of all the pendent rods 45 associated with the last eleven keys to the right of Figure 10, while the notch 190 for the 1 key and made wide enough, permits the spur 191 of the pendent rod 45 for said 1 key to pass said lower key-locking bar 186. Thus it is provided that none of the twelve keys but the 1 key may be operated when the carriage is at the tens-of-shillings denomination of a computing zone since no numeral higher than the 1 is ever typed at such denomination.

It may be observed here that the all-keys-locking mechanism, comprising the lever 146, its tongue 148 and the lock-elements 149, does not function at the tens-of-shillings denomination, it being sufficient for proper operation of the keys to merely lock all the keys but the 1 key as described at said denomination.

When the carriage leaves the tens-of-shillings denomination, or the farthings denomination, and thereby releases the corresponding jacks 56, the spring 88, associated with the corresponding master rack 64, co-operates to restore the corresponding distributive rack 68 and the described key-locking train extending therefrom.

Instead of typing farthings by means of upper-case types $\frac{1}{4}$, $\frac{1}{2}$, $\frac{3}{4}$ that are on the same type-bars 26 that have, respectively, the lower-case types 1, 2 and 3 as represented in the complement of numeral types diagrammed at Figure 12, the farthings may be typed by means of three farthings keys 204 that are additional to the twelve numeral keys 133 in the back row of the keyboard and may be disposed in the bottom row of the latter, Figures 3, 4, 5 and 9. Thus, the farthings may be typed without necessarily shifting the platen to upper case and, further, the farthings as well as the numerals from 0 to 11 may be typed in lower case in one style and in upper case in a different style as represented by the type-complement diagram, Figure 13, the different styles serving to distinguish, for example, debit amounts from credit amounts on a work sheet.

The three farthings keys 204 may be so disposed in the lower keyboard row that their key-levers 23 are adjacent the key-levers 23 for the 1, 2 and 3 keys in the upper keyboard row. Thus, pendent rods 205 on such additional farthings key-levers are disposed alongside of the pendent rods 45 for the 1, 2 and 3 keys of the upper row in order to engage, respectively, the same arms 46 of the 1, 2 and 3 pin-setting linkages. Each pendent rod 205 may have a lateral projection 203, Figure 3, extending in front of the lower end of the companion pendent rod 45 so that, like the latter, the pendent rod 205 may engage the arm 46 near its end.

In such additional-farthings-keys arrangement, each of the several pendent rods 45 and 205 has a spur 191 to co-operate with an upper key-locking bar 206 and an underlying key-locking bar 207. As represented in Figure 3, the key-locking bars 206, 207, respectively, are controlled by means of the farthings-denomination distributive rack 68 and the tens-of-shillings-denomination distributive rack 68, the connections between said racks 68 and bars 206, 207 being similar to those seen in Figure 2 and the parts of said connections being accordingly indicated, respectively, by the same reference numbers as in Figure 2.

The key-locking bars 206 and 207 have notches 208 adapted so that in the normal positions of said bars, line A, Figure 9, the spur 191 of any one of the pendent rods 45 or 205 may pass there-

through to pass said bars freely, thus permitting operation of any of the numeral keys in either the back row or front keyboard row.

When the carriage is at the farthings denomination of a computing zone and has depressed the farthings jack 56, the upper-key bar 206 is consequently moved leftward to the position, line B, Figure 9, so that unnotched portions 209 of said upper bar 206 block descent of all pendent rods but the pendent rods 205 associated with the additional farthings keys 204 thereby permitting operation of only these keys at the farthings denomination.

When the carriage is at the tens-of-shillings denomination of a computing zone and has depressed the tens-of-shillings jack 56, the lower key-locking bar 207 is consequently moved leftward to the position, line C, Figure 9, thereby blocking descent of all the pendent rods 45, 205, except the pendent rod 45 associated with the 1 key in the back row.

The all-keys-locking mechanism, comprising the lever 146, its tongue 148 and the key-locking elements 149, does not function to compel an operation of the case-shift mechanism at a farthings-denomination position of the carriage since the extra-keys 204 for farthings may be operated for typing farthings in lower case as well as in upper case at such denomination. Therefore, it will be understood there need be no provision, with the arrangement using the extra farthings keys 204, of a connection between the farthings jack 56 and the case-shift frame 33 such as is represented by the parts 157-161 of Figure 7. With said arrangement the key-locking elements 149 may be split as at 210, Figure 9, to permit passage of the spurs 191 of the pendent rods 205 of the extra farthings keys 204. When the carriage is at a punctuation-space position and has depressed the punctuation-space jack 111 or 112, the tongue 148 is consequently caused to be interposed at 154 thereby locking all the keys 133 in the upper row and also locking the three extra farthings keys 204 in the lower row of the keyboard.

When it is desired to type in upper case by means of any of the numeral keys 133 or 204 without computing, a case-shift key-lever 211, Figure 7, is depressed about its fulcrum 212 to rock the shift frame 33 through an intermediate arm 213, Figures 1 and 7. Said arm 213 and an arm 214 are integral with a sleeve 215 that is rotatably loose on a reduced portion 216 of the cross-shaft 34 of the case-shift frame 33. Thus, when the right case-shift key-lever 211 is depressed to rock the shift frame 33, the arm 214 is rocked counter-clockwise of Figure 7 to depress the link 126 to withdraw the latch 129 from the plate 130, Figure 1, for consequently disabling all the jacks 56, 111, 112, as hereinbefore described. But when the left or farthings case-shift key-lever 162 is depressed to rock the case-shift frame 33 to upper-case position, the arm 214, being loose on the case-shift frame cross-rod 34 is not actuated and, consequently, the jacks are not disabled at depression of said farthings case-shift key 162, but remain operative.

The operation of the key-locking mechanisms will be understood in detail from the foregoing descriptions and may be summarized as follows:

With either the Figure 2 or Figure 3 arrangement, the all-keys-locking mechanism, comprising the shoulders 153 associated with the several numeral keys, and the key-locking elements 149,

is operative through the jacks 111, 112 at a punctuation-space position of the carriage, to lock all of the numeral keys. In the Figure 2 arrangement, said all-keys-locking mechanism also serves to lock, primarily, all the keys 133 when the carriage has depressed the farthings jack 56, the latter then acting upon the all-keys-locking mechanism, to render the same effective, through the interponent bar 158 which depresses the all-keys-locking punctuation jack 112. Then, before the farthings can be typed by means of an upper-case character $\frac{1}{4}$, $\frac{1}{2}$ or $\frac{3}{4}$, Figure 12, the farthings case-shift key-lever 162 is depressed to select said upper-case types, and, concomitantly, the interponent bar 158 is withdrawn to release the depressed punctuation jack 112 with consequent unlocking of the keys relatively to the key-locking elements 149. However, the farthings jack 56 remains depressed at the typing of the farthings by said upper-case characters and, therefore, the key-locking bar 185 is in the line B position, Figure 10, to lock all the numeral keys except the first three keys from the left that type the farthings in upper case. At the tens-of-shillings-denomination position of the carriage, the depression of the corresponding jack 56 serves to shift the lower key-locking bar 186 to the line C position, Figure 10, thereby locking all the numeral keys except the 1 key since the latter is the only key ever used at the tens-of-shillings denomination.

In the Figure 3 arrangement, the all-keys-locking mechanism, comprising the spurs 191 and key-locking elements 149, does not function except at a punctuation-space position of the carriage. At a farthings-denomination position of the carriage, the farthings jack 56 is depressed and consequently the upper key-locking bar, 206 is shifted to the line B position, Figure 9, to lock every one of the numeral keys, except the three extra farthings keys 204, it being noted that each of the keys 0 to 11 in the back row of the keyboard is then locked. At the tens-of-shillings denomination position of the carriage, with the Figure 3 arrangement, the tens-of-shillings jack 56 is depressed and consequently the lower bar 207 is shifted to the line C position, Figure 9, thereby locking all the numeral keys except the 1 key in the back row of the keyboard, it being noted that the extra keys 204 in the front row are also locked at this time.

Variations may be resorted to within the scope of the invention, and portions of the improvements may be used without others.

Having thus described my invention, I claim:

1. In a combined typewriting and computing machine having computing-wheel drivers, the combination with numeral keys, a denomination-selecting carriage co-operative with said keys, denominational trains including, carriage-operated jacks and racks intermediate said jacks and drivers, and a mechanism for locking a predetermined portion of the number of said keys and having a connection to the rack of one of said denomination trains so as to be operable directly by said one train. 65

2. In a combined typewriting and computing machine and key-locking mechanism therefor, the machine having a typing unit, including numeral-type keys and a letter-feeding carriage, 5 surmounting a computing base having indexers corresponding to said keys, and register-bars, the combination with pendent rods extending down from said key-levers to actuate said indexers, and denominational trains operable by the carriage to shift said register-bars into index-receiving position relatively to said indexers, of spurs on said pendent rods, a shiftable key-locking bar adapted to clear normally said spurs of said pendent rods, and means operatively connecting said bar to a 15 part of a certain one of said denominational trains so that operation of said one train by the carriage shifts said bar into key-locking position relatively to said spurs.
3. In a combined typewriting and computing machine and key-locking mechanism therefor, the machine having a typing unit, including numeral-type keys and a letter-feeding carriage, 20 surmounting a computing base having indexers corresponding to said keys, and register-bars, the combination with pendent rods extending down from said key-levers to actuate said indexers, and denominational trains operable by the carriage to shift said register-bars into index-receiving position relatively to said indexers, of spurs on said 25 pendent rods, a plurality of shiftable key-locking bars each adapted to clear normally said spurs on said pendent rods and connections operatively connecting one bar to a part of one of said denomination trains, and the other bar to a part 30 of another one of said trains so that operation of said one or other train by the carriage shifts the corresponding bar to key-locking position relatively to said spurs, the bars being adapted individually to co-operate with different predetermined portions of the pendent rods to lock different 35 portions of the keys.

4. In a machine of the class described, the combination with a series of numeral keys, indexing members corresponding to and operable by 45 said keys, and a carriage cooperative with said keys to feed step by step in respect to indexable denominations of a computing zone, of a permutative locking mechanism for said keys including, a plurality of locking bars superimposed one upon 50 another and spanning all of said members, said bars being formed with permutative recessed and unrecessed portions and being normally positioned so that recessed portions clear all of said members for free operation of the latter, said bars being individually movable endwise from 55 their normal positions so that their unrecessed portions block operation of at least some of said members, each bar serving to block a different collection of said series of members, and means enabling the carriage to effect endwise movement of one bar at a predetermined one of said denominations and of another bar at another one of said denominations. 60

HENRY L. PITMAN.
